UNITED STATES PATENT OFFICE.

WHARTON B. McLAUGHLIN, OF NEW YORK, N. Y., ASSIGNOR TO THE McLAUGHLIN DEVELOPMENT COMPANY.

METHOD OF DESTRUCTIVE DISTILLATION.

1,012,684.

Specification of Letters Patent. Patented Dec. 26, 1911.

Application filed March 5, 1907. Serial No. 360,748.

To all whom it may concern:

Be it known that I, WHARTON B. McLAUGHLIN, a citizen of the United States, residing at New York, county of New York, 5 and State of New York, have invented a new and useful Improvement in Methods of Destructive Distillation, of which the following is a full, clear, and exact description, reference being had to the accompanying 10 drawings, which form a part of this specification.

My invention is particularly applicable for the purpose of distillation of wood to produce charcoal and by-products. It is 15 also useful for other purposes, such, for instance, as the treatment of coal, to produce coke and by-products of coal, and the treatment of acetate of lime for the production of acetone.

20 My method has for its object an improvement in the process of producing destructive distillation, particularly of wood, to produce charcoal and by-products.

I have discovered that if I pass a heating 25 medium a plurality of times in indirect contact with the material to be treated, reheating said medium between said passages, I not only increase the yield of the distillate, but increase and improve the quality of 30 the residuum. This is particularly the case where the destructive distillation is of wood to produce charcoal and by-products. In practice, with my process, applied to the production of charcoal, I have increased the 35 yield of acetate of lime about 65% and increased the yield of the charcoal 30%, and largely increased its value, more particularly in the manufacture of explosives.

As a heating medium, I prefer to use 40 steam, which I introduce initially in a superheated condition and reheat said steam between its passages.

I will now describe an apparatus by 45 which my improved process may be carried out.

In the drawings: Figure 1 is a horizontal section of apparatus on line 1—1, Fig. 2.

Fig. 2 is a vertical section on line 2—2, Fig. 1. Fig. 3 is a detail sectional view of pressure valve.

50

a is a steam pipe leading from the boiler.

b is a heater or superheater, heated by the burner pipes, *e*, *e*.

k is a flue to lead off the products of combustion from the burner pipes *e*, *e*.

55

c is the retort. In this retort is placed the material to be subjected to destructive distillation. The pipe *a*, after passing through the heater or superheater *b* extends to the retort and around the same as indicated at *f*. The pipe then returns to the heater or superheater *b*, then back again to and around the interior of the retort. I have shown six sections in the retort, although a less or greater number may be 60 used, corresponding to the heat units added. The pipe finally, at *g*, extends beyond the retort and may open directly into the atmosphere or to some point where it may be put to further use. Upon the section *g*, I prefer 65 to place a pressure valve *h* so as to control the circulation in the retort.

i is a pipe to lead the vapors to the condenser.

In practice, the steam which leaves the 75 boiler at a pressure say of 100 pounds, would have a temperature of about 170° centigrade. This should, in the heater, be superheated to say 450° centigrade.

I do not intend to limit myself, except 80 where specifically claimed, to the use of steam, or to a boiler as the means to heat the fluid.

Having now fully described my invention, 85 what I claim and desire to protect by Letters Patent is:

1. The method of effecting destructive distillation which consists in passing a heating medium in indirect contact with different parts of the material to be distilled and 90 reheating the medium between its several passages relative to the material.

2. The method of effecting destructive distillation which consists in successively

passing a column of superheated steam in
indirect contact with material to be dis-
tilled and reheating such column of super-
heated steam between its several passages
5 relative to the material so that the tempera-
ture of the steam in its several passages may
be uniform.

In testimony of which invention, I have
hereunto set my hand, at Philadelphia, on
this 27th day of February, 1907.

WHARTON B. McLAUGHLIN.
